LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY

CONTROL VALVE

Application filed June 7, 1929. Serial No. 369,129.

This invention relates to valves, but more particularly to a control valve adapted for use in connection with rock drills and similar machines to control the exhaust of fluid therefrom.

One object of the invention is to maintain the valve immovable in its chamber unaffected by the vibration of the machine to which it may be applied.

10 Other objects will be in part obvious and in part pointed out hereinafter.

In the drawings illustrating the invention and in which similar reference characters refer to similar parts,

15 Figure 1 is a sectional elevation of a portion of a rock drill equipped with a control valve constructed in accordance with the practice of the invention,

Figure 2 is a view similar to Figure 1 illustrating the manner in which the resilient handle may be inserted in the valve,

Figure 3 is a transverse view through Figure 1 on the line 3—3 looking in the direction indicated by the arrows, and

25 Figure 4 is a view similar to Figure 1 showing a modified form of the invention.

Referring more particularly to the drawings, and at first to the form of the invention illustrated in Figures 1 and 2, A represents a valve casing which may be an integral part of a rock drill cylinder B, only a portion of which is shown and having an exhaust passage C through which the motive fluid may flow to the atmosphere. The cylinder B is provided with a reciprocatory hammer piston D for delivering blows of impact to a working implement (not shown) and normally controls the exhaust passage C. A passage B' leading from a suitable source of pressure fluid supply opens into the front end of the cylinder.

The piston D carries an integral extension E which is guided by a front cylinder washer F forming a closure for the front end of the cylinder and said extension E is provided with flutes G adapted to interlock with suitable devices for imparting the rotary movement of the piston to the working implement against which the piston is adapted to strike.

50 In mechanism of the type to which the in-

vention is shown applied means are usually provided for constantly introducing fluid under pressure, such as compressed air, into the hole being drilled for removing the cuttings therefrom. Such means may consist of the well known air tube through which pressure fluid flows either intermittently or continuously through the drill steel into the drill hole. When drilling holes of moderate depth this method may suffice to maintain a clean rock face for the cutting bit of the working implement. Under certain conditions, however, as for instance, when drilling deep holes, the method of puff blowing or the continuous introduction of pressure fluid in small quantities is frequently found to be insufficient to remove the cuttings from the drill hole.

It is accordingly the aim of the present invention to equip the drilling mechanism with means for periodically introducing pressure fluid in large quantities into the drill hole to effect a thorough cleansing thereof whenever the means ordinarily provided for this purpose is found to be inadequate. To this end the casing A is provided with a bore H which preferably extends entirely through the casing to receive a control valve J having a recess K in its periphery which in one position of the valve J forms a continuation of the exhaust passage C. By forming the recess K in the side of the valve J a solid portion L remains in the valve and said portion L is of sufficient area to form a closure for the exhaust passage C in another position of the valve. Preferably the valve J is provided with a head O at one end adapted to bear against the casing A for preventing endwise movement of the valve in one direction.

The valve J is preferably of such length that an end P thereof extends beyond the casing A and the end P may, if desired, be of the same diameter as the body portion of the valve.

Means are provided for rotating the valve J and also to hold the valve immovable in the bore H unaffected by such vibration as may be set up in the apparatus to which the valve may be applied. To this end the pro-

jecting end P of the valve is provided with a transverse aperture Q and a transverse slot R in parallelism with the aperture Q and so arranged that its inner end S lies with-
in the bore H.

The aperture Q is adapted to accommodate a leg T of a resilient handle U and the slot R is adapted to accommodate a leg V of the handle U and having a hook W which, in the assembled position of the handle U, extends into a socket X in the valve J.

The legs T and V of the handle are connected by a curved spring portion Y which may be under sufficient tension to tend to spread the legs T and V and thus press the leg V firmly against the end of the casing A. If desired, notches Z and z may be formed in the end of the casing A to engage the leg V. Owing to the inherent tension of the spring portion Y of the handle and by reason of the fact that the leg T thereof is fixedly disposed in the end P of the valve, the head O of the valve will be pressed firmly against the end of the casing so that, irrespective of any vibration which may be set up in the apparatus to which the valve may be applied, the head will remain immovable in the bore H and will therefore only vibrate with the apparatus but not relatively thereto.

The notches Z and b may be suitably arranged to coincide with the limiting positions of the handle U . However, if desired, shoulders c and d may be provided on the end of the casing adjacent the notches Z and b respectively to act as an abutment for the leg V .

In the modified form of the invention illustrated in Figure 4, a resilient handle *e* is shown having two symmetrical legs *f* and *g*. Both legs are straight throughout their length and are joined at corresponding ends by a curved spring portion *h* tending to constantly spread the legs *e* and *f*. The leg *f* extends into the slot *R* wherein it is adapted to move and the leg *e* extends into the aperture *Q* wherein it is fixedly held by a pin *j* which extends transversely through the end *P* of the valve and engages a notch *k* in the leg *e*.

The operation of the device is as follows: During the normal operation of the machine, the valve J occupies the open position in which the recess K affords communication between the sections of the exhaust passage C so that the motive fluid may have a free path from the cylinder B to the atmosphere. In this position of the valve the leg V of the handle U is in engagement with the notch b. Whenever it is desired to effect a thorough cleansing of the drill hole, the valve J may be rotated to the closed position and all the pressure fluid flowing to the front end of the cylinder may then be directed through the flutes G into the hole being drilled and the

piston will remain immovable in the rearward end of the cylinder until the valve J is again opened. During the blowing operation the valve will be held against rotation by the leg V of the handle which then engages the notch Z.

The present invention has been found to function in an unusually efficient manner and is highly desirable for use in connection with drilling apparatus of the purpose described since the valve may be readily controlled by means located at and associated with only one end of the valve so that during its manipulation it will be unnecessary for the operator to expose his hand to the exhaust fluid issuing from the cylinder. Moreover, by thus arranging the handle the chances of injury to the operator are entirely eliminated as the handle in either of its limiting positions will be removed from any protuberances and sharp edges of the rock drill. In some mechanisms the close proximity of the handle to the apparatus wherewith it is associated may not be objectionable. In rock drills however, where the entire mechanism vibrates at a terrific rate it is essential that the handle be so located that it may be grasped without exposing the operator to contact with other portions of the drilling apparatus.

I claim:

1. A fluid controlled valve comprising a casing having a passageway therethrough, a bore in the casing intersecting the passageway, a valve in the bore controlling the passageway and having an extension beyond the casing, a handle having two legs resiliently urged apart, transverse bores in the valve extension adapted to closely receive one leg of said handle and loosely receive the other leg, and means in the valve extension coacting with the handle to hold the handle in the valve.

2. A fluid controlled valve comprising a casing having a passageway therethrough, a bore in the casing intersecting the passageway, a valve in the bore controlling the passageway and having an extension beyond the casing, a handle having two legs resiliently urged apart, transverse bores in the valve extension adapted to closely receive one leg of said handle and loosely receive the other leg, means in the valve extension coacting with the handle to hold the handle in the valve, and means in the casing coacting with the handle to retain the valve in position in the bore. 110 115 120

In testimony whereof I have signed this specification.

LEWIS C. BAYLES.
